UNITED STATES PATENT OFFICE.

JOHN FEGER ANCONA, OF READING, PENNSYLVANIA.

READING DEVICE.

1,248,779.

Specification of Letters Patent. Patented Dec. 4, 1917.

Application filed July 15, 1915. Serial No. 40,043.

To all whom it may concern:

Be it known that I, JOHN FEGER ANCONA, a citizen of the United States, residing at Reading, in the county of Berks and State of Pennsylvania, have invented or discovered certain new and useful Improvements in Reading Devices, of which the following is a specification, reference being had therein to the accompanying drawings.

10 This invention relates to an improved system of presenting reading matter, more particularly light fiction and the like, printed on both sides of long strips adapted to be wound up on rollers. In carrying the invention into effect certain means are provided whereby as a strip is being read on one side it may be readily unwound from one roller and wound upon another, and when the reading of the first side has been 20 completed the opposite side thereof may be conveniently presented to the reader, as it is unwound from the second roller and rewound on the first roller, without requiring any shifting of a holder, or any reversing 25 of the position of the holder in reading the printed matter from the second side of the printed strip, all as will hereinafter more fully appear.

In the accompanying drawings Figure 1 30 is a partly sectional elevation of a reading device embodying one form of the present invention. Figs. 2 and 3 are sections of the same on lines 2—2 and 3—3, respectively, Fig. 1, with the winding rollers omitted and 35 with the strip indicated in broken lines conventionally illustrating the same mostly wound on the rollers. Fig. 4 is a detail sectional view on line 4—4, Fig. 2. Fig. 5 is a detail section showing one of the mountings of the rollers. Figs. 6 to 9, inclusive, 40 are somewhat diagrammatic views illustrating the method of using the improved reading device. Fig. 10 is a partly broken away elevation illustrating a preferred form of 45 the invention somewhat different from that shown in Fig. 1, and Figs. 11 and 12 are partial elevations showing forms of the invention embodying operating means somewhat similar to that illustrated in Fig. 10.

50 Referring to the drawings, 12 denotes a frame or holder which will preferably be made of light sheet metal and which will be provided with a handle as 13 attached to said frame or holder in any suitable manner. 55 Mounted in said frame or holder 12 are two rollers A and B which are provided with

slits a for the reception of the opposite ends C and E of the reading strip, the opposite sides of said strip being denoted by F and G. The holder 12 comprises an extended 60 backing or steadyng plate D provided at its lower portion, or near the handle 13, with an opening 14 through which the reading strip will pass in running from one roller to the other, the upper edge 15 of said 65 backing plate, and over which the reading strip passes, being rounded to facilitate the passage of said strip.

Mounted at one end of the frame or holder 12 is a spring metal bracket 16 provided 70 with centering pivot studs 17 to engage one end of each of the rollers A and B, the said bracket having finger pieces 18 extending outward through slots in the end portions of the frame or holder 12. By means 75 of these finger pieces the end portions of the bracket 16 may be sprung outward, as denoted in dotted lines at the upper part of Fig. 1, when a roller A or B is to be engaged with or disengaged from a centering 80 stud 17. Fixed to the end of the frame or holder 12 opposite the bracket 16 are centering pivot studs 19, and mounted to rotate on the said studs 19 are pinions 20 provided 85 with lugs or dogs 21 adapted to enter notches in one end of each of the rollers A and B, so that when the said pinions are rotated the said rollers will be turned for the purpose of winding the reading strip off 90 from one roll and onto the other.

Mounted between the pinions 20, on a stud 22, is a gear wheel 23. The stud 22 has a portion extending outward through a slot 24 in the side of the frame or holder 12 and the outer end of said stud is entered by a screw 25 beneath the head of which is placed a holding spring 26 provided with rounded indented portions affording projections 27 adapted to enter 95 holes 28 in the frame or holder 12. By virtue of this construction the stud 22 may be moved in the slot 24 so as to bring the gear wheel 23 into engagement with one or the other of the pinions 20, and when shifted to a desired position said gear wheel will 100 be retained in place by the holding spring 26, as will be understood.

The gear wheel 23 is provided with a ratchet wheel portion 29 which rotates therewith, and which is preferably formed 110 integral with said gear wheel, as shown in Fig. 4. The ratchet wheel 29 is engaged

by a pawl-rack 30 pivotally mounted on a flexible slide or metal ribbon 31 passing between a guide plate 32 and a wall or flange on the frame or holder 12. The flexible slide 31, in the construction shown in Fig. 1, is provided with an operating pin 33 extending outward through a slot 34 formed in a portion of the frame or holder 12, so that by means of said operating pin 10 the pawl-rack 30 may be moved in a direction to partially rotate the ratchet wheel 29. The said flexible slide 31 is retracted by the coil spring 35 attached at one end to the frame or holder 12 and at its other end to 15 an arm on the said pawl-rack 30, and thus the said spring serves not only to retract the flexible slide 31 but also serves to hold the said pawl-rack yieldingly in engagement with the ratchet wheel 29 so that the pawl 20 rack may slide freely backward over the teeth of the ratchet wheel when retracted by the said spring 35.

From the foregoing it will be apparent that either of the rollers A or B may be 25 intermittently rotated, when desired, for the purpose of winding the reading strip onto one roller and off from the other, and as the said rollers will be rotated in opposite directions when engaged by the intermediate gear 30 wheel 33 one roller will be positively rotated to wind the reading strip thereon as the said reading strip is drawn from the other and freely rotating roller.

In the form of the invention shown in Fig. 10 the handle 13^a is formed of spring wire and one member of said handle is engaged with a pin 33^a attached to the flexible strip 31, so that when it is desired to rotate the gear wheel 23, for the purpose of moving the reading strip in one direction or the other, it is only necessary for the reader to compress one member of the handle, as indicated by dotted lines, to rotate the ratchet wheel 29 and the gear wheel 23 connected therewith, the handle assuming its normal shape by its own resilience, assisted, if need be, by the retracting spring 35 and the spring 35^a mounted in the spring wire handle 13^a.

In the form of the invention shown in Fig. 11 the handle 13^b is formed of two members jointed together at 36, and in this form of the invention a spring 37 will preferably be employed to return the yielding handle portion to its normal position after having been moved to the position denoted in dotted lines to operate the ratchet wheel and gear wheel for the purpose of rotating one of the winding rollers.

The form of the invention shown in Fig. 12 is similar to that shown in Fig. 11 excepting that a coil spring 38 is interposed between the members of the handle 13^c for the purpose of holding the movable member 65 of the handle in its normal position or re-

turning it thereto after it has been displaced therefrom.

From the foregoing it will be understood that the reading strip may be gradually fed from one roller A or B to the other, at the pleasure of the reader; and when the reader has completed the perusal of one side of the said reading strip the other side thereof may be brought into reading position in front of the supporting plate D without requiring any adjustment of the rollers A or B, or without reversing the direction of travel of the said reading strip over the backing or supporting plate D. This will be understood by reference to sheet 3 of the drawings. Fig. 6 shows one end C of the reading strip engaged with the roller B when the latter is empty, and when the said roller is rotated in the direction indicated by the arrow the reading strip will be drawn upward over the supporting plate D with the face F of said reading strip outward. When the said reading strip has been wound upon the roller B, as denoted in Fig. 7, and the roller A is empty, the end E of the reading strip will be disengaged from the roller A and will be lifted up over the plate D and the roller B and will then be brought down to the position denoted by dotted lines in Fig. 7, so as to be carried around over the plate D and the roller B be again engaged with the roller A, as diagrammatically illustrated by Fig. 8. Such a disposition of the reading strip will reverse the same and bring the face G outward into reading position, and thus when the roller A is positively rotated, through the mechanism hereinbefore described, to wind the reading strip thereon, said reading strip will be drawn upward over the supporting plate D and 105 will be finally wound upon the roller A, as diagrammatically illustrated in Fig. 9, in readiness to be again wound upon the roller B when one end of said reading strip shall have been disengaged from the said roller B 110 and the strip again disposed as diagrammatically shown in Fig. 6. From this it will be understood that both sides of the reading strip may be exposed to the view of the reader and may be gradually fed from one 115 roller to the other in a simple and convenient manner as the reading progresses.

Having thus described my invention I claim and desire to secure by Letters Patent:—

1. In a reading device to be supported manually by the reader, the combination with a holder provided with a handle, of two rollers mounted on said holder and adapted to detachably engage the opposite ends of a 125 reading strip, pinions for rotating said rollers, a shiftable gear wheel mounted between said pinions and adapted to be moved into engagement with either of them, and means for intermittently rotating said gear wheel, 130

said device comprising means whereby the path of travel of a reading strip may be changed when said strip is reversed and is to be reversely fed.

5 2. In a reading device to be supported manually by the reader, the combination with a holder provided with a handle, of two rollers mounted on said holder and adapted to engage the opposite ends of a reading strip, pinions for rotating said rollers, a shiftable gear wheel mounted between said pinions and adapted to be moved into engagement with either of them, means for intermittently rotating said gear wheel, a 15 stud on which said shiftable gear wheel is mounted, and a spring connected with said stud and provided with projections, said holder having a slot in which said stud is movable and having also two holes to receive said projections to hold said stud in either position to which it may be adjusted.

3. In a reading device to be supported manually, the combination with a holder provided with a handle, of two rollers mounted on said holder and adapted to engage opposite ends of a reading strip, pinions for rotating said rollers, a shiftable gear wheel mounted between said pinions and adapted to be moved into engagement with either of them, means for intermittently rotating said gear wheel, said means comprising a ratchet wheel, a spring-pressed pawl-rack engaging said ratchet-wheel, a manually movable operating pin, and a 30 spring-retracted, flexible metal ribbon between said pin and said pawl-rack, said ribbon being guided within said holder.

4. In a reading device to be held by the reader, the combination with a holder provided with a handle, of two rollers mounted on said holder and adapted to engage the opposite ends of a reading strip, pinions for

rotating said rollers, a shiftable gear wheel mounted between said pinions and adapted to be moved into engagement with either of them, means for intermittently rotating said gear wheel, said means comprising a ratchet wheel, a rack engaging said ratchet wheel, a manually movable operating pin, a spring-retracted flexible metal ribbon within said holder and between said pin and said pawl-rack, and a movable handle part connected with said pin to operate said connection.

5. In a reading device, the combination with a holder provided with a handle and having centering pivot studs, two rollers the opposite ends of which are engaged by said pivot studs, said rollers being adapted to hold, detachably, the opposite ends of a reading strip, a centrally mounted spring bracket 60 within said holder and in which bracket one set of said pivot studs are mounted, said bracket having parts extending outward through said holder and terminating outside of said holder in finger pieces by means of which the said pivot studs may be moved away from the ends of said rollers when the latter are placed in or removed from said holder.

6. In a reading apparatus, the combination with a holder comprising a backing or supporting plate, of a reading strip printed on both sides, two rollers adapted to engage and hold the opposite ends of said reading strip, and means for intermittently rotating either of said rollers to feed the said reading strip from one to the other, said apparatus comprising means whereby the path of travel of said reading strip may be changed when said strip is reversed so that either 80 side thereof may be presented outward over said backing or supporting plate.

In testimony whereof I affix my signature.
JOHN FEGER ANCONA.
